(57) **CLAIM**

The ornamental design for a connection module, as shown and described.

DESCRIPTION

FIG. 1 is a top, front, left side perspective of a connection module showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof;

FIG. 7 is a front elevation view thereof; and,

FIG. 8 is a bottom, rear, right side perspective thereof.

The even-broken lines shown in the drawings represent unclaimed environment and form no part of the claimed design.
